(57) **CLAIM**

The ornamental design for an electrical connector for heated wearables control as shown and described.

DESCRIPTION

FIG. 1 is a perspective view of the control for heated wearables;

FIG. 2 is a front view thereof;

FIG. 3 is a right side view thereof;

FIG. 4 is a left side view thereof;

FIG. 5 is a top end view thereof;

FIG. 6 is a bottom end view thereof;

FIG. 7 is a rear view thereof;

FIG. 8 is a perspective view showing a second embodiment of the control for heated wearables;

FIG. 9 is a front view of the second embodiment;

FIG. 10 is a right side view of the second embodiment;

FIG. 11 is a left side view of the second embodiment;

FIG. 12 is a top end view of the second embodiment;

FIG. 13 is a bottom end view of the second embodiment; and,

FIG. 14 is rear view of the second embodiment.

The broken lines in the drawings depict portions of the electrical connector for heated wearables control that form no part of the claimed design.
